UNITED STATES PATENT OFFICE.

ALBERT J. GURNEY, OF CANTON, OHIO, ASSIGNOR TO THE AMERICAN MINE DOOR CO.,
OF CANTON, OHIO, A CORPORATION OF OHIO.

SIGNALING SYSTEM FOR MINES.

Application filed November 7, 1923. Serial No. 673,329.

To all whom it may concern:

Be it known that I, ALBERT J. GURNEY, citizen of the United States, residing at Canton, in the county of Stark and State of Ohio, have invented certain new and useful Improvements in Signaling Systems for Mines, of which the following is a specification.

This invention relates to an improved signaling system for mines, being especially designed for use in coal mines, and seeks, among other objects, to provide a system wherein suitably located annunciators will be automatically energized incident to the passage of a mine car along the tracks of the mine.

The invention seeks, as a further object, to provide a signaling system wherein the use of switches or contact springs will be eliminated.

And the invention seeks, as a still further object, to provide a signaling system wherein it will be unnecessary to equip the mine cars with any special apparatus to effect the operation of the system.

Other and incidental objects will appear hereinafter.

In the drawings:

Figure 1 is a diagrammatic view showing my improved system as it would be installed in the main and side entries of a mine,

Figure 2 is a detail side elevation showing a typical hanger employed,

Figure 3 is a detail side elevation showing another typical hanger employed, but of slightly different design, and

Figure 4 is a detail elevation showing the manner in which the circuits through the annunciators are closed by means of the trolley of the mine cars.

Referring now more particularly to the drawings, the usual trolley wire of the in-going track of the main entry of a mine is indicated at 10 and the trolley wire of the out-going track at 11. Similarly, the trolley wire of the track of a left side entry is indicated at 12 while the trolley wire of the track of a right side entry is indicated at 13. Further, I have illustrated the trolley wire of a left cross-over track between the main tracks, at 14, and the trolley wire of a right cross-over track at 15. In conjunction with the trolley wires or main conductors, I employ a plurality of pendant wires or auxiliary conductors, one of which is indicated at

16. As shown in Figure 2, these conductors are arranged above and over the trolley wires and are supported at their ends by hangers indicated as a whole at 17. A typical hanger is illustrated but since said hanger has been made the subject of a separate application, it is not necessary to herein go into the details of the device. However, it should be observed that the hangers include set bolts 18 which may be adjusted for tensioning the conductors 16 and also carry clamps 19 for supporting the trolley wires in addition to the conductors. Auxiliary hangers, indicated as a whole at 20, are also employed for supporting the intermediate portions of the conductors as well as also supporting the trolley wires, a typical auxiliary hanger being shown in Figure 3. This hanger, like the hanger of Figure 2, has also been made the subject of a separate application and will not, therefore, be described in detail.

As shown in Figure 1, the conductor 16 is arranged over the trolley wire 10 in advance of the junction of the wire 12 therewith and arranged over the wire 10 to extend across the junction of the cross-over track wire 15 therewith is a similar conductor 21 connected with the conductor 16 by a wire 22. Arranged over the wire 11 in advance of the junction of the wire 13 therewith, is a conductor 23, and arranged over the side entry track wires 12 and 13 are like conductors 24 and 25, while similar conductors 26 and 27 are arranged over the cross-over track wires 14 and 15 respectively. In series with the conductors 16 and 21 is a green or other suitably colored pilot lamp 28 as well as a preferably red signal lamp 29 electrically grounded as indicated at 30, the lamp 28 being arranged adjacent the main in-going track and the lamp 29 adjacent the left side entry track. As is usual, the trolley wire will, of course, be more or less slack, so that, as a mine car proceeds along the main in-going track and the trolley of the car travels along the wire 10, the trolley wheel, conventionally illustrated in Figure 4 at T, will, in being pressed upwardly against the trolley wire, lift said wire into direct contact with one of the conductors but failing in this, will, in any event, contact both the trolley wire and the conductor wire engaging first with the conductor 16 and then with the conductor 21 to close a circuit through the lamps 28 and 29.

29. Accordingly, the motorman of the car will be able to see the green pilot lamp 28 while any other motorman of a car on the left side entry track, will be apprised by the 5 signal lamp 29 of the approach of a car on the main track.

Attention is now particularly directed to the fact that the circuit through the conductor 16 will be maintained closed substantially throughout the length of said conductor and will likewise be maintained closed practically throughout the length of the conductor 21 so that after the lamps have been energized, said lamps will be 10 maintained energized for a considerable time or until the car on the main in-going track has progressed to a point out of the way. The length of the conductor wire employed will, therefore, determine the approximate interval during which the display 15 of a signal will be maintained and, of course, such interval may be either lengthened or shortened as desired by simply varying the length of the conductor wire.

20. In series with the conductor 23 is a signal lamp 31 adjacent the right side entry track, a pilot lamp 32 adjacent the main out-going track, a signal lamp 33 adjacent the right cross-over track, and a signal lamp 34 adjacent the left side entry track, these several lamps being connected with the ground 25. Accordingly, when the trolley wire 11 is lifted by the trolley of a car upon the main out-going track, all of said lamps will 30 be energized and signals thus given to maintain the out-going track clear. In series with the conductor 24 is a pilot lamp 35 adjacent the left side entry track, and a signal lamp 36 adjacent the main in-going track, these lamps being electrically grounded as indicated at 37. Thus, lifting of the trolley 35 wire 12 by the trolley of a car upon said track will result in the energization of a pilot lamp for the benefit of the motorman 40 while the lamp 36 will give a stop signal at the in-going track of the main entry.

45. In series with the conductor 25 is a pilot lamp 38 adjacent the right side entry track, a signal lamp 39 adjacent the main out-going track, a signal lamp 40 adjacent the right cross-over track, and a signal lamp 41 adjacent the left side entry track, these several lamps being also electrically grounded at 30. Thus, when the conductor 25 is energized from the trolley wire 13, the proper signals will be given. In series with the conductor 26 is a signal lamp 42 adjacent the in-going track of the main entry, a pilot lamp 43 adjacent the left cross-over 55 track, a signal lamp 44 adjacent the out-going track of the main entry, and a signal lamp 45 adjacent the right side entry track, these several lamps being electrically grounded as indicated at 46. Energization 60 of the conductor 26 from the trolley wire 14

will thus effect display of the proper signals. In series with the conductor 27 is a signal lamp 47 adjacent the in-going track of the main entry, a pilot lamp 48 adjacent the right cross-over track, a signal lamp 49 adjacent the out-going track of the main entry, and a signal lamp 50 adjacent the right side entry track, these lamps being connected with the ground 46. Accordingly, when the conductor 27 is energized from the trolley wire 15, the proper signals will be given. Suitable annunciator housings may be provided for the signal lamps and, as suggested in Figure 1, several lamps are in any instance where possible, arranged in a single housing, while reflectors, as indicated diagrammatically at 51, are employed in conjunction with the lamps for focusing the rays thereof in the direction desired.

Having thus described the invention, what is claimed as new is:

1. In a signaling system, the combination of a main conductor, means supporting the main conductor for flexing movement away from its normal position, an annunciator, a trolley having an element to travel along the main conductor flexing said main conductor, and an elongated auxiliary conductor electrically connected with said annunciator and insulatingly supported adjacent the main conductor to extend substantially parallel thereto substantially in the path of the flexing movement of the main conductor for direct engagement by the latter conductor when flexed closing a circuit through said annunciator.

2. In a signaling system, the combination of a trolley wire, means supporting the trolley wire for flexing movement away from its normal position, an annunciator, a trolley having an element to travel along the trolley wire flexing said trolley wire, and an auxiliary conductor wire electrically connected with said annunciator and insulatingly supported adjacent the trolley wire to extend substantially parallel thereto substantially in the path of the flexing movement of the trolley wire for direct engagement by the trolley wire when flexed closing a circuit through said annunciator.

3. In a signaling system, the combination of a main conductor, an annunciator, an auxiliary conductor electrically connected with said annunciator and insulatingly supported adjacent the main conductor to extend longitudinally thereof, a trolley to cooperate with said conductors closing a circuit through said annunciator, and means common to both conductors supporting said conductors and adjustable for tensioning the auxiliary conductor independently of the main conductor.

4. In a signaling system, the combination of a main conductor, an annunciator, an auxiliary conductor electrically connected

with said annunciator and insulatingly supported in spaced relation to the main conductor to extend longitudinally thereof, a trolley to cooperate with said conductors 5 closing a circuit through said annunciator, and means common to both conductors supporting said conductors and adjustable to affect the auxiliary conductor independently of the main conductor and vary the spacing 10 between said conductors.

5. In a signaling system, the combination with a main track, and a side track, of a trolley wire associated with both tracks, means supporting said wire for flexing 15 movement away from its normal position, an auxiliary conductor wire insulatingly supported adjacent the trolley wire at the main track, an annunciator adjacent the main track, an annunciator adjacent the side track, said annunciators being electrically connected with said auxiliary conductor wire, and a trolley having an element to travel along the trolley wire flexing the trolley wire into direct engagement with the 20 said auxiliary conductor wire closing a circuit through the latter wire and through said annunciators.

6. In a signaling system, the combination with a main track, and a side track, of a trolley wire associated with both tracks, means supporting said wire for flexing movement away from its normal position, an auxiliary conductor wire supported adjacent the trolley wire at the side track, an 25 annunciator adjacent the side track, an annunciator adjacent the main track, said annunciators being electrically connected with said auxiliary conductor wire, and a trolley having an element to travel along the trolley wire flexing the trolley wire into direct engagement with the 30 said auxiliary conductor wire closing a circuit through the latter wire and through said annunciators.

7. In a signaling system, the combination with a main ingoing track, a main outgoing track, and a cross over track extending between the former tracks, of a trolley wire associated with all of said tracks, means supporting said wire for flexing movement 35 away from its normal position, an auxiliary conductor wire insulatingly supported adjacent the trolley wire at the ingoing track, an annunciator adjacent the ingoing track, an annunciator adjacent the outgoing track, an annunciator adjacent the cross over track, said annunciators being electrically connected with said auxiliary conductor wire, and a trolley having an element to travel along the trolley wire flexing the trolley wire into direct engagement with the auxiliary conductor wire closing a circuit through the latter wire and through said annunciators. 40

8. In a signaling system, the combination with a main ingoing track, a main outgoing

track, and a cross over track extending between the former tracks, of a trolley wire associated with all of said tracks, means supporting the trolley wire for flexing movement away from its normal position, 70 an auxiliary conductor wire insulatingly supported adjacent the trolley wire at the cross over track, an annunciator adjacent the ingoing track, an annunciator adjacent the outgoing track, an annunciator adjacent the cross over track, said annunciators being electrically connected with said auxiliary conductor wire, and a trolley having an element to travel along the trolley wire flexing the trolley wire into direct engagement with the auxiliary conductor wire closing a circuit through the latter wire and through said annunciators. 75

9. In a signaling system, the combination with a main ingoing track, a main outgoing track, and a cross over track extending between the former tracks, of a trolley wire associated with all of said tracks, means supporting said wire for flexing movement away from its normal position, an auxiliary conductor wire insulatingly supported adjacent the trolley wire at the outgoing track, an annunciator adjacent the ingoing track, an annunciator adjacent the outgoing track, an annunciator adjacent the cross over track, said annunciators being electrically connected with said auxiliary conductor wire, and a trolley having an element to travel along the trolley wire flexing the trolley wire into direct engagement with the auxiliary conductor wire closing a circuit through the latter wire and through said annunciators. 90

10. In a signaling system, the combination with a main ingoing track, a main outgoing track, a cross over track between the former tracks, and a side track extending from one of the main tracks, of a trolley wire associated with all of said tracks, means supporting said wire for flexing movement away from its normal position, an auxiliary conductor wire insulatingly supported adjacent the trolley wire at one of said tracks, an annunciator adjacent each of said tracks, said annunciators being electrically connected with said auxiliary conductor wire, and a trolley having an element to travel along the trolley wire flexing the trolley wire into direct engagement with the auxiliary conductor wire closing a circuit through the latter wire and through said annunciators. 110

11. In a signaling system, the combination with a main ingoing track, a main outgoing track, a cross over track between the former tracks, a side track leading from the ingoing track, and a side track leading from the outgoing track, of a trolley wire associated with all of said tracks, means supporting said wire for flexing movement away 115 120 125 130

from its normal position, an auxiliary conductor wire insulatingly supported adjacent to the trolley wire flexing the trolley wire into direct engagement with said auxiliary conductor wire at one of said tracks, an auxiliary conductor wire closing a circuit annunciator adjacent each of said tracks, through the latter wire and through said annunciator each of said tracks, the latter wire being electrically connected with each of said annunciators.

In testimony whereof I affix my signature.
ALBERT J. GURNEY. [L. S.]
